UNITED STATES PATENT OFFICE.

CHARLES H. KOSTER, OF BROOKLYN, NEW YORK, ASSIGNOR TO THE UNEXCELLED FIREWORKS COMPANY, OF SAME PLACE.

DESIGN FOR DECORATIVE FABRIC.

SPECIFICATION forming part of Design No. 18,941, dated February 26, 1889.

Application filed June 12, 1888. Serial No. 276,882. Term of patent 7 years.

To all whom it may concern:

Be it known that I, CHARLES H. KOSTER, a citizen of the United States, and resident of Brooklyn, in the county of Kings and State of New York, have invented and produced a new and original Design for Decorative Fabrics, of which the following is a specification.

My invention relates to designs applicable to textile fabrics and adapted to decorative 10 and other similar purposes, the leading feature of said design being a series of distinct longitudinal stripes—preferably three in number—of substantially equal width, applied to a continuous web, one of the marginal stripes 15 being decorated with stars, and further ornamented by a series of similar figures placed at suitable intervals and representing the eagle with wings displayed or extended and grasping in its talons a sheaf of arrows or 20 other national emblem.

Referring to the accompanying drawing, in which the figure represents my design, the reference-letter a denotes a strip or web of bunting or other fabric, upon which are displayed a series of longitudinal stripes, b c d, 25 preferably three in number and of equal or substantially equal width. One of the marginal stripes, as b, is decorated by a series of stars, e, sprinkled upon the continuous stripe at suitable uniform intervals, and upon the 30 star-decorated stripe thus formed I also place a series of figures at intervals, representing an eagle, d', with wings displayed and grasping in its talons a sheaf of arrows.

The distinctive features of the design are 35 the longitudinal stripes displayed upon a continuous web of fabric, one of the marginal stripes being decorated by stars and by a series of figures representing the national eagle.

What I claim is—

The design for a bunting or other fabric herein set forth, the same consisting of the parallel continuous stripes, one of the outer or marginal stripes being sprinkled with stars and decorated by a series of figures representing the eagle, substantially as described. 45

Signed at New York city, in the county and State of New York, this 8th day of June, A. D. 1888.

CHARLES H. KOSTER.
